UNITED STATES PATENT OFFICE.

EDWARD BAKER, OF ONEONTA, NEW YORK.

SUIT-BOX.

1,319,263.

Specification of Letters Patent. Patented Oct. 21, 1919.

Application filed December 9, 1918. Serial No. 265,979.

To all whom it may concern:

Be it known that I, EDWARD BAKER, a citizen of the United States, residing at Oneonta, in the State of New York, have invented new and useful Improvements in 5 Suit-Boxes, of which the following is a specification.

This invention relates to a suit box formed of paper or paste-board and designed for 10 articles of clothing, the box being, however, adapted for other purposes.

One of the objects is to provide a box in which the cover and the box proper are each formed of blanks of the same size and 15 configuration, as distinguished from boxes in which the cover is formed from a blank somewhat larger than the blank used in the construction of the box proper.

A further object is to provide a blank, 20 the end portions of which are formed in such manner that a main central tongue is provided with edge portions extending at an incline with reference to the extreme edge of the blank, thereby permitting a given 25 degree of movement between the elements of the cover when the edge portions or flaps are folded into position and permitting the construction of a cover from the same size of blank as that used for the box.

30 In the drawings,

Figure 1 is a view of the blank from which the box is made, the same blank being employed for the top.

Fig. 2 shows a folded corner section, in 35 perspective.

In carrying out my invention, I employ

a blank, the main portion of which is designated 10, the end flaps being shown respectively at 12 and 13 and being separated from the main portion of the blank by scored lines 40 15 and 16. The side flaps are designated 17 and 18 and the scored portions thereof are shown at 19 and 20.

Each end portion is cut away so that the edge 22 is at an incline with reference to 45 the extreme edge of ends 23. Each end portion is provided with slits 24 extending at an angle as shown and adapted to be engaged by the tongues 26 of the flaps 17 and 18, these 50 tongues being provided with rounded ends 27 and with hooked portions 28, the latter positively engaging the edges of the slits 24 when the flaps are folded into position for forming the box proper or the cover therefor.

55 It will be understood that the inclined portion 22 permits of a given degree of movement between interlocked end flaps and side flaps, for the purpose indicated.

60 What is claimed is:

In a device of the class described, a box and a separate cover therefor, said box and cover being formed of blanks of the same size including side and end flaps of the same contour and formed for interlocking engagement, the side edges of the end flaps being cut away at an incline allowing relative movement between adjacent side and end flaps when the latter are interlocked and permitting the cover to fit over the box.

70 In testimony whereof I affix my signature.
EDWARD BAKER.
